CAP

Virginia R. New Weatherman, 2325 Susquehanna Road,
Roslyn, Pa. 19001

Filed June 21, 1973, Ser. No. 372,093

Term of patent 14 years

Int. Cl. D2—03

U.S. Cl. D2—250

FIG. 1 is a front elevational view of a cap showing my new design;

FIG. 2 is a top plan view of the cap;

FIG. 3 is a side elevational view of the cap as seen from the right;

FIG. 4 is a rear elevational view of the cap; and

FIG. 5 is a bottom plan view of the cap.

I claim:

The ornamental design for a cap, as shown.
